ATTORNEYS

UNITED STATES PATENT OFFICE.

HERBERT BEAUMONT DAY, OF DETROIT, MICHIGAN; EVA ALEXANDER ADMINISTRATRIX OF SAID HERBERT BEAUMONT DAY, DECEASED.

TURRET-TOOL HOLDER.

Application filed October 24, 1924. Serial No. 745,683.

To all whom it may concern:

Be it known that I, HERBERT BEAUMONT DAY, a citizen of the United States, and a resident of Detroit, in the county of Wayne and State of Michigan, have invented certain new and useful Improvements in Turret-Tool Holders, of which the following is a specification.

This invention is an improvement in 10 turret tool holders.

An object of this invention is to provide a turret tool holder so designed and constructed as to hold a plurality of standard tool bits, ground for different operations by 15 the operator, and to permit accurate and quick presentation of the tools to the work in their proper order.

With this and other objects in view, as will appear as the description proceeds, this 20 invention consists of the novel features of construction, combinations of elements and arrangements of parts hereinafter to be fully described and claimed.

A full and complete understanding of the 25 invention may be obtained from a consideration of the following detailed description, taken in connection with the accompanying drawing forming a part of this specification, it being understood that the invention is not 30 confined to the showing thereof, but may be changed or modified so long as such changes and modifications mark no material departure from the salient features of the invention, as specifically pointed out and claimed.

35 In the accompanying drawing wherein similar reference characters designate similar parts throughout the several views,

Figure 1 is a vertical sectional view of the complete device,

40 Figure 2 is a vertical sectional view taken on the line 2-2 of Figure 1, and looking in the direction indicated by the arrows,

Figure 3 is a side elevation of the nut;

45 Figure 4 is a view similar to Figure 2 with the parts in different relative positions,

Figure 5 is an end elevational view of the turret, and

Figure 6 is a fragmentary detail sectional view thereof.

50 In the specific embodiment of the invention illustrated in the accompanying drawing, the numeral 1 indicates a supporting metallic shank which may be either supported upon the carriage of a lathe or be formed

as an integral part thereof. The upper vertically extending portion 2 of the shank 1 is substantially cylindrical and is provided centrally of one of its faces with a recess 3 and an aperture 4 extending from the center of the recess to the opposite face.

A cylindrical turret 5 having a central aperture 5^a is designed to engage one of the faces of the cylindrical portion 2 and has rigidly secured to it by countersunk rivets 60 as shown the ratchet plate 6 which is normally disposed within the recess 3.

An annular groove 7 is provided on the turret to receive a felt packing ring to prevent the entrance of dust to the ratchet. A 70 bronze bushing 8 traverses the turret and plate 6 and acts as a bearing through which the supporting bolt 9 passes for holding the turret in operative position with respect to the shank 1.

Extending from the inner portion of the 75 turret are a plurality of square apertures 10 for receiving standard lathe tool bits 11 which have been ground for different operations by the operator. These bits are held in position by set screws 12 screwed in from 80 the periphery of the turret and engaging the tool. The outer surface 13 is knurled from its outer edge for part of the radial distance to its inner edge to permit easy rotation of the turret by hand but has the 85 portion thereof that is overlapped by the head 14 of the bolt 9 smooth to prevent scoring of the under face of the bolt head and to permit facile rotation of the turret 5 when the nut 15 on the threaded end 16 of the bolt 90 has been loosened.

A spring pressed pawl pin 17 is disposed within an aperture 18 in the shank 1 and is held in position by a set screw 19. The free 95 end 20 of the pin is notched to provide a shoulder 21 for engagement with the shoulders 22 on the teeth 23 of the plate 6.

A key 24 which preferably is of a Woodruff type has a driving fit with a key seat 25 in the shank of the bolt 9, the key seat 25 being semi-circular in cross section and the key 24 extending radially outward from the bolt shank for engagement with a key-way 26 in the supporting shank 1. The key 24 is driven into the seat 25 after the bolt has 100 been extended through the bronze bushed assembly of turret 5 and ratchet plate 6 and radially protruding portion of the key slides 105

freely in the key-way 26 so that the assembly can be secured to the supporting shank 1 through the agency of the bolt 9 and nut 15 and the bolt also will be held against rotation in the bore 4 of the supporting shank 1. A series of spaced apertures are provided extending inwardly from the periphery 27 of the nut 15 to accommodate a spanner wrench for manipulating the same.

10 The operation of the device is as follows: Suitable tools are associated with the turret as has been described, and the nut 15 being loosened, rotation of the turret in one direction is permitted by reason of the fact that the pin 17 is cammed outwardly in opposition to the pressure of its spring by the curved portion of the teeth 23. The turret is rotated to a position as indicated in Figure 4 when the tool which is to be used is above the center of the work. The operator then rotates the turret in a reverse direction until the shoulder of the pin 17 engages the shoulder of the appropriate tooth 23 and prevents further rotation thereof. The nut

15 is then tightened and the tool is held firmly in its position.

Having thus fully described the invention, I claim as new and desire to secure by Letters Patent:

The combination with a supporting shank 30 having a substantially cylindrical portion recessed on one of its faces and a punctured centrally of said recess, of a turret having means for supporting a plurality of radially extending tools, a ratchet plate rigidly secured 35 to the turret and disposed within the said recess, a bushing traversing said turret and plate, a bolt traversing said bushing and shank with its head in engagement with the outer face of said turret, a nut threaded on 40 the bolt for maintaining the parts in assembled relation, means preventing rotation of said bolt with respect to said shank, and means permitting rotation of the turret in one direction and preventing continued rotation in the opposite direction.

HERBERT BEAUMONT DAY.
